UNITED STATES PATENT OFFICE

ROBERT WILLIAM TYSICK, OF PERTH, ONTARIO, CANADA, ASSIGNOR OF ONE-HALF TO
FREDERICK J. PUBLOW, OF PERTH, ONTARIO, CANADA

DUSTPAN

Application filed August 11, 1930, Serial No. 474,445, and in Canada April 25, 1930.

My invention relates to dust pans.

Dust pans at present on the market have the objection that they lack stability and rigidity and in many cases the handles break off and the pan itself crumples and becomes useless under ordinary wear.

The objects of my invention are to eliminate all the drawbacks which I have found in dust pans now on the market, and to render my dust pan strong and durable with the pan of a sufficient weight of metal that will not crumple under ordinary use, and in which the handle will have the desired durability and be attached in a manner in which it is not liable to become detached.

In carrying out my invention, I also make the metallic portion from a single blank so that rigidity is obtained.

With the above and other objects in view, it will be made clear as the specification proceeds that my invention relates to an improved construction and arrangement of parts which I have definitely pointed out in my appended claim.

In the drawing,

Fig. 1 is a plan view of the blank from which my dust pan is made, the dotted lines indicating the manner in which the blank is bent.

Fig. 2 is a semi-perspective view of the blank with the edges bent.

Fig. 3 is a perspective view of the back wooden portion of the pan.

Fig. 4 is a perspective view of the pan.

Like characters of reference refer to like parts in the several figures.

Referring to the drawing,

A dust pan in accordance with this invention includes a body part A of sheet metal. The metallic sheet being bent upon lines 13, 14 and 15 to provide a bottom, a pair of sides, a pair of oppositely disposed lugs 10 extending inwardly from the rear ends of the sides and an upwardly extending flange at the rear of the body portion. The lugs 10 are positioned against the rear face of the flange and provided with orifices 11.

The pan also includes a back wall 16 of trapezoidal contour having its sides and bottom edges grooved as at 17. The back wall is

positioned between the rear ends of the sides of the pan, and the grooved sides of such wall receive the lug 10 and the grooved bottom edge of such wall receives the upwardly extending flange at the rear of the bottom 55 of the pan.

The flange 12 engages with the groove 17 in the lower edge of the back portion, while the lugs 10 engage with the groove 17 in the sides of the back portion, and when a dust pan is so assembled, rivets 20 are driven through the back member and hole 11 to secure the blank "A" to the back portion 16.

The handle 19 is secured in position by gluing and by a nail 21 and said handle is 60 further provided with an eyelet 22 by means of which it may be hung up.

This dust pan is of an extremely strong nature and has an exceedingly long lifetime, and will not go out of use with ordinary care 70 and work.

While I have described a specific form embodying my invention, I do not wish to be limited, but only inasmuch as I have done in the claim which follows.

What I claim as my invention is:

In a dust pan, a sheet metal body part formed of a flat bottom, a pair of sides, oppositely disposed, inwardly extending apertured lugs at the rear ends of the sides and an upwardly extending flange at the rear end of said bottom and opposing the forward faces of the lugs, a back wall positioned between the rear ends of the sides and having grooved sides and bottom edges, said lugs and flange being extended into said grooved edges, and holdfast devices for connecting the flange and lugs to said back wall.

Signed at Perth, Ontario, this 31st day of July, A. D. 1931.

ROBERT WILLIAM TYSICK.
